UNITED STATES PATENT OFFICE.

GRAFFIN WATKINS, OF WASHINGTON, MISSOURI, ASSIGNOR TO ROBERTS, JOHNSON & RAND SHOE COMPANY, OF ST. LOUIS, MISSOURI, A CORPORATION OF MISSOURI.

BOOT.

941,116.

Specification of Letters Patent.

Patented Nov. 23, 1909.

Application filed August 30, 1909. Serial No. 515,126.

To all whom it may concern:

Be it known that I, GRIFFIN WATKINS, a citizen of the United States, residing at the city of Washington, in the county of 5 Franklin and State of Missouri, have invented certain new and useful Improvements in Boots, of which the following is a specification, reference being had therein to the accompanying drawings.

10 This invention relates to boots, especially to that class suitable for use in automobiling, riding, etc., and has for its object to provide a boot in which the leg part is formed like a legging which is secured to the foot part 15 and provided with straps, lacing, or other suitable means for holding said leg part around the calf of the wearer.

The novelty of this invention resides in the peculiar shape in which the inside quarter 20 and the front portion of the leg part are cut and the peculiar manner in which said parts are fitted together, which is herein-after more fully described and pointed out in the claims.

25 In the drawings forming part of this specification, in which like numbers of reference denote like parts wherever they occur, Figure 1 is a front view of the boot, and Figs. 2, 3, and 4, are perspective views showing the leg part open.

The boot is made of strong flexible material, preferably leather, and is provided with the sole 1 to which the heel 2 is fastened. The one-piece side 3 which is 30 sewn or otherwise suitably secured to said sole, extends partly over the instep of the foot and upwardly to the top of the leg part 4. The quarter 5, which is, also, secured to said sole extends partly over said instep and 35 upwardly to a line above the ankle. The cap or toe 6 is secured to said sole and extends rearwardly on each side of the foot, where it is sewn to said side 3 on one side and to said quarter 5 on the other side.

40 The vamp 7, which is sewn to the cap 6, extends over the front of the foot and is sewn to edge 8 of the side 3 and to the edge 9 of the quarter 5. The tongue 10 is secured to the edges 11 and 12 of the side 3 and quarter 5, respectively, which are provided with the eyelets 13 through which the lace 14 passes and secures said edges together over the instep.

45 The side, or flap 15, is secured to the inner side of edge 16 at the top of said quarter,

and protrudes through the slit 17 in said edge. The portion 18 of said side, which is overlapped by said flap, extends upwardly from said slit, and preferably a little higher above the ankle than the edge 16. The 60 edge 19 of the piece 20 is secured to the edge 21 of the flap 15 by the strap 22, which stiffens the front portion of said leg part and prevents same from wrinkling. Said piece 19 overlaps the front portion of side 65 3 when the leg part 4 is secured about the calf of the wearer. The lower edge of said flap extends downwardly from said slit, thence curves forwardly and arches over the instep to the middle thereof, where it meets 70 the lower edge of said piece 20 which continues to arch over said instep and then curves rearwardly and upwardly until it terminates in the edge 23. The arch 24 formed as hereinabove described prevents 75 said flap from pressing on the instep and allows the free action of the ankle of the wearer.

The strap 25, which is secured to the upper edge of piece 20, is adapted to hold the 80 upper portion of said leg part closely around the calf of the wearer by the buckle 26 which is secured to the upper portion of side 3. The strap 27, is secured to the lower portion of piece 20 and is adapted to be 85 wound around said leg part and held by buckle 28, secured to the upper portion of side 3. The back edges 29 and 30 of side 3 and quarter 5, respectively, are held together by the strip 31, which is sewn thereto and 90 extends from the heel to the top of edge 29, and the back edge 32 in the side 15 extends from the edge 16 to the top of edge 29 and is held thereto by said strip 31. Said strip 95 is provided with a plurality of slits 33 through which the strap 27 is passed and held in place around the leg part by the straps 34 formed between each pair of slits. The whale-bone 35, or any other suitable stiffening member, which is inserted underneath said strip 31 adjacent the edges 29 and 32, is held in place by the stitching, and prevents said leg part from wrinkling. The piece 20 and the side 15 are covered on the inside with the linings 36 and 37, respectively, and the side 3 is provided with the lining 38, which extends upwardly from a line above the ankle and covers the remaining portion of said side.

When it is desirable to make the leg part 110

of said boot of material which differs from the material forming the shoe part, it is necessary to form the side 3 in two pieces. This is accomplished by forming the lower portion of said side with a quarter having its top edge extending around one side above the ankle from the back end of edge 16 to the edge 11, and the leg portion of said side is secured along its bottom edge to the top 10 edge of said quarter. The back edge of said leg portion is secured to the back edge of flap 15 which is secured to quarter 5 in the manner hereinbefore described.

I claim:

15 1. A boot having a one-piece side, a one-piece quarter sewn along the back edge to said side and extending to a line above the ankle, a two-piece flap sewn to the back edge of said side above said quarter, said flap 20 being sewn along a portion of the bottom edge thereof to the inner side of a portion of the top edge of said quarter, a slit in said top edge through which the remaining lower portion of said flap protrudes, said remaining lower portion extending downwardly from said slit and adapted to arch 25 the instep and cover the remaining portion of said top edge of said quarter, and means for securing the loose portion of said flap 30 to said side.

2. A boot having a one-piece side, a one-piece quarter sewn thereto, a two-piece flap sewn to said side and to the inner side of a portion of said quarter, the lower portion of 35 said flap extending outwardly through a slit in said quarter and adapted to arch the instep, means for securing said quarter and said side together over the instep, and means for securing the loose portion of said flap to 40 said side.

3. A boot having a one-piece side, a one-piece quarter sewn thereto, a two-piece flap sewn to said side and to the inner side of a portion of the upper edge of said quarter, 45 means for securing said quarter and said side together over the instep, the lower portion of said flap extending outwardly through a slit in said upper edge and adapted to arch said instep and cover the remaining 50 upper portion of said quarter and a portion of said securing means, and means for

securing the loose portion of said flap to said side.

4. In a boot, the combination of a quarter having a slit in the upper edge thereof, a 55 flap secured to the inner side of said quarter along the top edge thereof extending from the back seam to the edge of said slit, the remaining lower portion of said flap extending through said slit and downwardly therefrom covering the remaining upper portion of said quarter in front of said slit and adapted to arch the instep, a one-piece side 60 secured to the back edges of said quarter and said flap, a stiffening member secured along the back seam between said side and said flap, and means for securing the loose portion of said flap to said side.

5. In a boot, the combination of a quarter having a slit in the upper edge thereof, a 70 flap sewn to the inner side of said quarter along the top edge thereof extending from said slit to the back edge of said quarter, the remaining lower portion of said flap being adapted to extend through said slit and downwardly therefrom covering the remaining upper portion of said quarter in front of said slit and to arch the instep, a one-piece side 75 sewn along the back edge to said quarter and said flap, a lace adapted to secure said quarter and said side together over the instep and to be partly covered by said lower portion of said flap, a strip adapted to cover the entire back seam, a whale-bone secured underneath said strip and extending 80 from the top of said seam to the top of said quarter, a pair of buckles secured to the top portion of said side, a strap secured to the top part of the loose portion of said flap and adapted to be held by one of said buckles, 85 a strap secured to the bottom part of said loose portion and adapted to be wound around the leg part of said boot and to be held by the other of said buckles, and a plurality of slits in said strip through which 90 said last-mentioned strap is passed.

In testimony whereof I have affixed my signature in presence of two witnesses.

GRiffin Watkins.
